DESIGN FOR A FINDER FOR CAMERAS

Lawrence R. Martin, Rochester, N. Y., assignor to Eastman Kodak Company, Rochester, N. Y., a corporation of New Jersey

Application April 19, 1938, Serial No. 76,600

Term of patent 14 years

To all whom it may concern:

Be it known that I, Lawrence R. Martin, a citizen of the United States, residing at Rochester, in the county of Monroe and State of New York, have invented a new, original, and ornamental Design for a Finder for Cameras, of which the following is a specification, reference being had to the accompanying drawing, forming part thereof and in which:

Fig. 1 is a rear perspective of the finder for cameras embodying my new design, and

Fig. 2 is a front perspective of said finder for cameras also showing my new design.

I claim:

The ornamental design for a finder for cameras, as shown.

LAWRENCE R. MARTIN.
